Primary Examiner — Jonathan J Han*Assistant Examiner* — Christen Pilar Brown(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;

FIG. 2 is a side view thereof; and,

FIG. 3 is a rear perspective view thereof.

The broken line showing of the unshaded inner region forms no part of the claimed design. The broken lines depicting the remainder of the shoe form no part of the claimed design.
